FIG. 5

FIG. 6

FIG. 7

FIGURE 1 is a front elevational view of a lighting fixture for gardens, terraces and the like showing our new design;

FIGURE 2 is a rear elevational view thereof;

FIGURE 3 is a top plan view thereof;

FIGURE 4 is a bottom view thereof;

FIGURE 5 is a front elevational view of a modified form of the lighting fixture shown in FIGURE 1, with the standard shown broken away in part to indicate indeterminate length.

FIGURE 6 is a top plan view of said other form; and

FIGURE 7 is a bottom view of said other form.

We claim:
The ornamental design for a lighting fixture for gardens, terraces and the like, substantially as shown and described.
